UNITED STATES PATENT OFFICE

WILLIAM J. GRADY, OF DECATUR, ILLINOIS, ASSIGNOR TO FARIES MANUFACTURING COMPANY, OF DECATUR, ILLINOIS, A CORPORATION OF ILLINOIS

DESIGN FOR A FLOOR LAMP

Application filed October 27, 1931. Serial No. 41,538. Term of patent 3½ years.

To all whom it may concern:

Be it known that I, WILLIAM J. GRADY, a citizen of the United States, residing at Decatur, in the county of Macon and State of Illinois, have invented a new, original, and ornamental Design for a Floor Lamp, of which the following is a specification, reference being had to the accompanying drawing, forming part thereof, in which—

The figure is a side elevation showing my new design.

I claim:

The ornamental design for a floor lamp, as shown.

WILLIAM J. GRADY.
